UNITED STATES PATENT OFFICE.

WILLIAM A. SNEED, OF HILLSBORO, MARYLAND.

PLUMB-LEVEL.

No. 830,681.

Specification of Letters Patent.

Patented Sept. 11, 1906.

Application filed May 19, 1906. Serial No. 317,789.

To all whom it may concern:

Be it known that I, WILLIAM A. SNEED, a citizen of the United States, residing at Hillsboro, in the county of Caroline and State of Maryland, have invented new and useful Improvements in Plumb-Levels, of which the following is a specification.

This invention relates to a plumb-bob-level device for use either on horizontals or 10 perpendiculars; and it consists in the construction and arrangement of the several parts which will be more fully hereinafter set forth.

In the drawings, Figure 1 is an elevation of 15 the combined plumb and level device embodying the features of the invention. Fig. 2 is a detail enlarged elevation of a portion of the same, showing parts thereof removed. Fig. 3 is a transverse vertical section on the 20 line 3 3, Fig. 2.

Similar numerals of reference are employed to indicate corresponding parts in the views.

The numeral 1 designates the stock of the 25 instrument, which may be constructed as usual and of any suitable length, width, and thickness. In the center and adjacent to one end the level and plumb devices are located, both being of precisely the same construction or arranged so that the one may be 30 used for truing horizontals and the other for operating in conjunction with perpendicular structures. As each of the plumb and level devices is of exactly the same construction 35 and varies only in the change of position, the description of one will apply to the other. The stock 1 at the points where the level and plumb devices are located has circular openings 2 formed therein and head-slots 3, 40 which normally communicate with the said openings. In addition lateral slots 4 are formed in the stock, for a purpose which will be presently explained. In each of the slots 2 a metallic cylinder 5 is mounted and is fully 45 open at opposite ends. In the upper central portion of each cylinder 5 a slot 6 is formed which communicates with the head-slot 3, and secured on the upper part of the cylinder and projecting within the slot 3 are fulcrum- 50 ears 7, disposed on opposite sides of the slot 6. A fulcrum-head 8 is arranged between the ears 7 and has terminal cone-bearings 9, of any suitable nature, engaging the said ears, and from the said head a rod 10 depends and 55 is connected at its lower end to a bob 11, the slot 6 being sufficiently long to permit the

rod 10 to swing unretardingly therein. Projecting outwardly from diametrically opposite points of the cylinder 5 and in planes at right angles to the plane of suspension of the 60 rod 10 are adjusting-arms 12, consisting of flat strips of metal secured to the cylinder and movably projected into the slots 4. The outer ends of the arms 12 are formed with 65 arcuate slots 13, which are struck from the center of the cylinder 5 and are engaged by headed studs 14, said studs being preferably in the form of set-screws. These arms 12 by their adjustment may be caused to take up 70 any irregularities or inequalities in the level or plumb devices which may arise from wear or other causes.

Normally the level or plumb device, including the rod 10 and bob 11, hangs centrally with respect to the cylinder 5, and any 75 inequalities in a horizontal or a perpendicular structure will be instantly indicated by the movement of the rod 10 and bob 11 to either one side or the other of the central plane of the cylinder 5 and in accordance with the 80 direction of the inequality. From the opposite ends of the cylinder glass sight-plates 15 are disposed and held in place by annular covering or binding plates 16, which are secured by suitable means to the stock 1. 85 These covering or binding plates fully inclose the slots 4 and also the slot 3, and from the exterior nothing is exposed except the sight-plates 15, the said binding-plates, the rods 10, and bobs 11. 90

The improved combined plumb and level will be found exceptionally advantageous in its operation and use and is superior in many ways to the ordinary spirit or double level and plumb device. 95

Having thus described the invention, what is claimed is—

1. The combination with a stock, of a level or plumb comprising a cylinder having diametrically-opposed adjusting-arms with terminal arcuate slots therein extending transversely thereof, set-screws engaging said slots and connected to the stock, a rod movably projecting into the cylinder and fulcrumed on the latter, a bob on the free extremity of the rod, and sight-plates applied against opposite ends of the cylinder. 100

2. In a device of the class set forth, the combination of a stock having an opening therethrough and a head-slot normally communicating with said opening, and adjusting-slots also formed in the stock in planes at 105

right angles to the head-slot, a cylinder in the said opening provided with diametrically opposed arms entering the said adjusting slots, the arms being terminally slotted, set 5 screws engaging the slots of the arms and stock, a fulcrum-head movably held on the upper portion of the cylinder within the head-slot, means for supporting the fulcrum-head, a rod movably depending into the cyl-

inder from the fulcrum-head, a bob on the 10 lower extremity of the rod, and sight-plates secured against opposite ends of the cylinder.

In testimony whereof I affix my signature in presence of two witnesses.

WILLIAM A. SNEED.
